(57) CLAIM

The ornamental design for a chain mounted clevis snap hook, as shown and described.

DESCRIPTION

FIG. 1 is an upper side perspective view of the chain mounted clevis snap hook;

FIG. 2 is a reduced scale side elevational view thereof;

FIG. 3 is a right end elevational view thereof;

FIG. 4 is a top view thereof;

FIG. 5 is a bottom view thereof; and,

FIG. 6 is a side elevational view of a second embodiment of the chain mounted clevis snap hook as disclosed in FIG. 1.
